UNITED STATES PATENT OFFICE

FRANK M. SALISBURY, OF DUNDALK, MARYLAND, ASSIGNOR TO THE GLENN L. MARTIN CO., OF BALTIMORE, MARYLAND, A CORPORATION OF MARYLAND

AIRPLANE FLOTATION SYSTEM

Application filed October 18, 1929. Serial No. 400,568.

My invention relates to aircraft emergency flotation systems and has particular reference to apparatus incorporated therewith which greatly increases their effectiveness, reliability, simplicity and efficiency. It is the result of continuation in the development of the emergency flotation system comprising the subject matter of a joint application Serial No. 379,776.

10 The instant application is based on the fact that, in the event of a forced landing upon water, an airplane will sink unless effective provision is made to float it and on the experience gained by practical operation of airplane emergency flotation systems in service which indicated that further development was necessary if their maximum effectiveness was to be attained.

15 The inventions which comprise the two identified applications involve to some extent the use of similar apparatus but the instant invention substitutes a rearwardly located inverted open bag adapted to act as a flotation body for the tail section in lieu of the closed rear bag heretofore used and functions in a manner differing from that described in the earlier application insofar as control of the sealing function of cylinder-piston control mechanisms and the method of inflation 20 of the rearwardly located flotation bag are concerned and in addition a balanced flotation is obtained.

25 One object of my improved system is to assure the floating of a disabled aircraft when it is compelled to alight upon water.

Another object is to simplify the operation of an emergency flotation system.

Another object is to reduce the weight, number and cost of parts comprising an 30 emergency flotation system.

Another object is to economize space by more efficiently utilizing that which was formerly occupied by a deflated compacted rear bag, its storage compartment, transfer valve mechanisms and higher capacity pressure reservoir.

Another object is to isolate flotation bags from each other after their initial inflation thus to prevent excessive accidental loss of 35 flotation gas.

Another object is to enable the pilot to control the reverse flow of flotation gas from the bags.

Another object is to enable the pilot to control the relative buoyancy of the bags in 40 the system to thus balance his craft upon the water.

Apparatus of this character is required to be simple, light, occupy a minimum of space when not in use, not introduce parasitic resistance, when emergency arises it is imperative that it shall function instantly with a minimum expenditure of time and effort on the part of the pilot. Inflatable bags fore and aft have been used as a means of floating 45 a disabled airplane but experience with the auxiliary apparatus required for their operation has shown that deficiencies existed in the systems. Compressed air to be used for inflating the bags required cumbersome tanks 50 of considerable weight for retention of an adequate supply of air to provide sufficient displacement to support the weight of an airplane and the crew. Substitution of a bottle of liquefied CO₂ gas solved the problem 55 of excessive weight and space occupied by the type of pressure tank formerly used but it introduced other difficulties which are overcome by the instant invention. For example, the rapid expansion of liquefied CO₂ gas 60 when released from the bottle to the pipes leading to the flotation bags caused rapid fall in temperature, a temperature so low as to destroy the effectiveness of check valves as heretofore used in systems of this type, in fact 65 the valve elements were frozen together. Freezing of the valves frequently caused the isolation of one or more bags from the system thus concentrating the gas pressure to the remaining bag and causing its disruption. 70 The exceedingly small increment of time required for the bags to inflate from a source of pressure amounting to approximately 1000 pounds per square inch necessitates the release of the bags from their storage compartments in advance of inflation that 75 serious damage to the aircraft structure be prevented.

The system herein described and illustrated comprises forwardly located inflat- 80

85

able bags with their storage compartments and associated mechanisms in number and size as required by the weight and design of the airplane together with a rearwardly located open flotation bag which automatically entraps air when more or less submerged in water. This type of bag does not require a storage compartment or door release mechanism because it is not ejected from the fuselage. The elimination of a rear compacted flotation bag together with the associated storage compartment, door release and transfer valve mechanism, and the substitution of an inverted open bag conserves the space formerly occupied by a bag compartment thereby making it available for cargo storage. In addition to the reduction of weight by the aforesaid eliminations, a reduction in capacity and weight of tanks required for storage of liquefied gas required for initial inflation of the forwardly located bags is obtained. The forwardly located bags are normally deflated and stored in compartments within the fuselage adjacent the outer surface of the craft which location is such as not to offer resistance to the airstream.

The compartments are normally closed by locked doors, preferably spring hinged, to automatically open outwardly when released by their locks. Means is provided whereby the locks are automatically opened in advance of bag inflation that the bags may not meet with resistance when leaving their compartments. Novel locking and pressure transfer mechanism is provided by which unlocking and opening of doors followed by inflation and ejection of the forwardly located bags is assured in proper sequence for reliable and safe operation. Gas for inflation of the forward gas bags is obtained from a liquefied CO₂ supply because of the minimum volume and weight occupied by a high pressure storage reservoir of this type which may be stored in any available place, to more efficiently utilize a limited space.

The solution of the enumerated problems was still short of applicant's objective, viz., the provision of a complete flotation system which will function effectively under ultra adverse conditions such for example as the loss of stored gas pressure previous to requirement for emergency flotation; or, loss of flotation due to rupture of a bag or of the pipe leading thereto; or, in case of a ruptured bag, loss of gas from the intact bags through the pipe lines leading to the defective bag; or to unbalancing of the craft due to shifting the center of gravity. The instant invention guards against these specified contingencies by providing manually operated means whereby compressed air supplements or replaces that from the CO₂ pressure storage tank, to reinflate the remaining bags thereby enabling the pilot to float his craft and to apportion displacement fore and aft

thereby preventing disaster due to changed position of the centers of buoyancy and gravity.

The position of the center of gravity of the plane while in flight is regulated by well known conventional means which is ineffective to balance the craft when it is more or less submerged in water. The movement of the center of gravity would be caused by the crew being compelled to leave the cockpit and find refuge on the wings or top of the fuselage. If the center of buoyancy locates directly above the center of gravity the craft will balance, otherwise the tail section will rise or fall until the aforesaid condition is corrected by the pilot. The instant invention provides means by which the pilot can balance his craft when it is floating upon the surface of water.

My system will be understood by reference to the following identified drawings, their description and the explanation of the mode of operation.

Fig. 1 is a plan view of the forward portion of an airplane cut away to show the interior arrangements of certain elements of my flotation system but omitting all flight control mechanisms which are not involved in my invention.

Fig. 2 is a plan view of one of my cylinder-piston mechanisms as adapted to act as a pressure transfer valve, manually operable pressure seal and to operate a door latch mechanism.

Fig. 3 is a view of the mechanism of Fig. 2 looking at the piston rod end.

Fig. 4 is a view of the mechanism of Fig. 2 looking at the end opposite to that of Fig. 3.

Fig. 5 is a cross-section of mechanism Fig. 2 with addition of a push rod extension to the piston rod thereby adapting it to act as a latch for the storage compartment door and as means for manually reversing the position of the piston head as a valve member.

Fig. 6 is a plan view of an airplane cut away to show the interior arrangements of the elements as shown in somewhat different arrangement but operating the same as in Fig. 1 and to show the addition of an inverted open flotation bag in the tail section.

Fig. 7 is a cross section through C-C of Fig. 6 to show my inverted open flotation bag supported by fastening to the bulkheads within the fuselage and adapted to float the tail section when it becomes more or less submerged in water.

Fig. 8 is a cross section A-A of an air pressure control valve as shown in Fig. 6.

Fig. 9 is a cross section B-B of the valve showing the operating handle and valve disc turned to a different position from that shown in Fig. 8.

Fig. 10 is a side elevation view of an airplane partially submerged in water and

floated by forwardly and rearwardly located flotation bags.

Fig. 11 is a front elevation view of the floating airplane illustrated in Fig. 10 and showing an ejected bag at each side of the fuselage.

In Fig. 1 an airplane fuselage is shown in outline at 15, wings 16, power plant and propeller 17, flotation bag storage compartments 18, storage compartment doors 19, 10 spring hinges 20, door catches 21, piston rods 22, piston rod lock members 23, cylinder-piston valve mechanisms 24-25, attached by lugs 26 to fuselage 15, piston heads 27, flotation bags 28-29 attached by cables 30 to fuselage 15, high pressure gas reservoir 31, 15 gas valve 32, gas valve opening cable 33, cable handle 34, outlet pipe 35 leads from valve 32 to branch pipes 36 which lead to inlets 37 of cylinder-piston mechanisms 20 24-25, flexible tubes 38-39 lead from outlets 40 of cylinder-piston mechanisms 24-25 to flotation bags 28-29. Cable 41 is attached at one end to piston rod 22 at 42 and at the 25 other end to ring 43. A support 44 is provided for ring 43 when in position to release piston rod 22. A spring 45 is attached at 46 to fuselage 15 and is provided with a hook 47 for a purpose hereinafter described. 30 Pipes 48-49 lead from cylinder-piston mechanisms 24-25 to valve 50 which is provided with an operating handle 51. Pipe 52 leads from valve 50 to a conventional air pump 53 which is provided with operating 35 means 54.

In Fig. 5 is shown interior details of cylinder-piston mechanisms 24-25 and their associated piston rod and lock members. Piston head 27 and lock members 23 are shown by solid lines in its initial position previous to 40 inflation of flotation bags and also subsequent to their inflation. The pistons 24-25 and lock members 23 are shown by dotted lines in position immediately following the 45 release of gas from reservoirs 31 to inlets 37. At 55 is shown a packing washer adapted to seal the opening through the cylinder head around piston rod 22 at 56 when piston head 27 is forced to the dotted position by 50 high pressure entering the cylinder at 37 and acting on piston head 27.

In Figs. 6 and 7 is shown the system of Fig 1 with my improved devices incorporated therein. Corresponding parts of Fig. 1 are 55 correspondingly numbered. At 60 is shown a flotation bag differing from bags 28-29 in respect to the method of inflation, it does not require a storage compartment, release mechanism or initial inflation by means other 60 than the entrapping of air when its lower portion is submerged in water. It is fastened in position as by cables 61 attached to fuselage 15 at 62. Portions of elevator and rudder controls are shown at 63.

65 Cross sectional view Fig 7 is taken through

C-C of Fig. 1 to show the open bottom portion of rear flotation bag 60 and to show the manner of its normal suspension from the fuselage members, whereas under water flotation conditions it is forced upward against the fuselage members by entrapped air pressure. At 64 is shown a pipe leading from bag 60 to a valve 65 which is shown in cross section by Figs. 8 and 9.

Manual inflation and buoyancy control valve 65 is illustrated by Figs. 8 and 9 and comprises a body 66 supported by a structural member 67 in any convenient manner. Body 66 has a chamber 68 communicating with inlet 69 and outlets 70-71-72-73. A disc valve member 74 is retained against a ground seat on the interior wall of body 66 by spring 75 and is adapted to be rotated by handle 76. Valve disc 74 is provided with two radially disposed slots in its contacting surface one of which 77 communicates with chamber 68 and the other 78 is adapted to communicate outlet 73 with either outlet 70-71-72 according to the instant position of disc 74 as controlled by handle 76 or to a position wherein chamber 68 is closed. Manual pressure applied to handle 76 against spring 75 unseats disc valve member 74 thereby opening outlets 70-71-72-73 to chamber 68 and releasing pressure from the rear flotation bag 60 and from the lines leading to mechanisms 24-25 to atmosphere. A return check valve 79 may be incorporated with chamber 68 and may be seated by spring 75 until unseated by air pressure from pump 53 as shown in Fig. 8, or a check valve may be incorporated with the conventional air pump 53 in lieu of 79. Check valves in the air lines are permissible because the pressure is low compared to that from the CO₂ reservoir and freezing due to rapid expansion cannot take place. The cubic content design of the two forward bags is equal to the supply of gas within the reservoir and inasmuch as the rear bag is not inflated by the CO₂ supply, the size and weight of the reservoir is reduced from that which would be required for gas supply to a third bag. Elimination of this weight and that of associated mechanism by the instant invention is a very considerable item.

Occasion having arisen for the airplane to alight upon water, the pilot releases gas from the high pressure reservoir 31 through valve 32 by pulling cable 33 with handle 34. High pressure gas then passes through pipes 36 to the inlets 37 of cylinder-piston mechanisms 24-25, acts on piston heads 27 to move piston rods 22 to a position in which door catches 21 are released from piston rod lock members 23 to thus permit spring hinges 20 to open doors 19, and in which position piston head 27 opens outlets 40 to inlets 37 thus releasing the high pressure gas through tubes 38-39 to forward flotation bags 130

28—29. The storage compartment doors 19 having opened provides free exit of two forward bags to the position shown in Figs. 6, 10, 11. A rear bag is not shown in Fig. 1, because non-adjustable flotation means are assumed to more or less float the tail section.

After release of gas from the high pressure source to the cylinder-piston door release and transfer valve mechanisms and its passage thereafter to the forward flotation bags, the pilot pulls cable 33 to move piston head 27 to an intermediate position within its cylinder thus isolating the inlet port 37 from the outlet port 40 to prevent flow of gas to or from either bag through pipe 38 and places cable ring 43 on the hook 47 attached to spring 45 which is fastened to the fuselage structure at 46. Thereafter at the time of servicing the flotation system, replacement of high pressure reservoir 31 and replacement of the forward bags in their storage compartments, the pilot returns cable ring 43 to position 44 at which it remains until the system is again brought into use. In the event that removal of the cable ring from hook 47 is overlooked and to guard against subsequent failure of the system due to that fact spring 45 is provided and which is normally in a free condition whether or not the cable ring is placed on the associated hook. In the event of again operating the flotation system, piston rod 22 pulls cable 41 and extends spring 45 accordingly. In the absence of this precaution and should the pilot fail to remove ring 43 from support 44, piston head 27 would be restrained by cable 41 to a position wherein entrance of pressure to bag 28 from cylinder 24 is impossible and high pressure gas from reservoir 31 would then concentrate in cylinder 24—25 and bag 29. Inasmuch as the combined design capacity of the two bags is such as to balance the volume of gas contained in reservoir 31 after expansion, failure to inflate one bag overloads the other by 100% thereby quite likely causing disruption of the remaining bag, loss of the aircraft and jeopardizing the lives of the members of the crew.

The emergency landing upon water having been accomplished it then becomes necessary to balance the craft, in other words to restore the center of buoyancy. In the event that the tail of the craft is riding higher than the forward end, the transfer valve 65 can be turned to a position shown in Fig. 9 wherein the air entrapped in the rear bag as shown in Fig. 10 is permitted to escape through vent 73 and the tail of the craft will assume a level position in relation to the forward end. Conversely, if the tail of the craft is lower than the forward end, valve 65 can be turned to a position shown in Fig. 8 at 77 wherein air can be forced into the rearwardly located bag by the manually operable

air pump 53 to thus bring the tail on a level with the forward end.

In the event that the right wing of the craft tilts downward due to insufficient inflation of the corresponding bag, the transfer valve 65 can be turned to a position as shown in Fig. 8 at 77 wherein the manually operable air pump 53 can increase the displacement of the bag to thus restore the craft to balance.

In the event that the left wing of the craft tilts downward, the valve 65 can be turned to a position opposite to that shown in Fig. 8 at 77 wherein air can be forced into the flotation bag by the manually operable air pump 53 thus restoring the craft to balance.

In the event that a lateral unbalanced condition is caused by shifting of the position of the crew, the valve 65 can be turned to a position corresponding to the valve outlet leading to the highest bag and wherein flotation gas can escape from the bag to thus restore equilibrium of the craft.

Having described my invention I claim,—

1. In an aircraft emergency flotation system, inflatable closed bags attached to said aircraft, means for inflating said bags, an inverted open bag located within said aircraft, said open bag adapted to entrap air when its opening is submerged in water, the relative size and location of said bags on said aircraft adapted to substantially uniform flotation of said craft upon water.

2. In an aircraft emergency flotation system closed inflatable bags attached to said aircraft, means for inflating said bags; an inverted open bag located within said aircraft, said open bag adapted to entrap air when its opening is submerged in water, means for varying the displacement volume of said open bag whereby substantially uniform longitudinal flotation of said aircraft is obtained.

3. In an airplane, an emergency flotation system comprising a multiple number of inflatable closed bags attached to and laterally located forwardly in relation to the fuselage structure of said airplane, manually controlled means for inflating said bags; an inverted open bag rearwardly located within said fuselage, manually operable means for inflating said open bag; said open bag adapted by its entrapped air capacity and coaction with said closed bags to float the tail section of said airplane.

4. In an airplane, an emergency flotation system comprising a multiple number of inflatable closed bags attached to and laterally located to float the forward section of the fuselage structure of said airplane, manually controlled means for inflating said bags; an inverted open bag rearwardly located within said fuselage and adapted by its entrapped air capacity to float the tail section of said airplane.

5. In an airplane, an emergency flotation

system comprising a multiple number of inflatable closed bags attached to and laterally disposed forwardly in relation to the fuselage structure of said airplane, means for inflating said bags; an inverted open bag attached to and rearwardly located within said fuselage, means for regulating the inflation displacement of said inverted bag, supplemental manually operable means for selectively supplementing the inflation of either of said bags, whereby flotation is obtained proportionate to the unbalanced weight of said airplane.

6. In an airplane, an emergency flotation system comprising a multiple number of inflatable bags attached to and laterally located forwardly in relation to the fuselage structure of said airplane, manually controlled means for inflating said bags; an inverted open bag rearwardly located within said fuselage and adapted by its air trapping capacity to float the tail section of said airplane; means for manually controlling the displacement volume of said inverted open bag.

7. In an airplane, an emergency flotation system comprising a multiple number of inflatable bags attached to and laterally located forwardly in relation to the fuselage structure of said airplane, manually controllable means for inflating said bags; an inverted open bag rearwardly located within said fuselage and adapted by its air trapping capacity to float the tail section of said airplane; means for simultaneously reducing the displacement volume of said bags.

8. In an airplane, an emergency flotation system comprising a multiple number of inflatable closed bags attached to and laterally disposed forwardly in relation to the fuselage structure of said airplane, means for ejecting said bags from said fuselage, means for inflating said bags; an inverted open bag attached to and rearwardly located within said fuselage, manually operable supplemental means for selectively inflating either of said bags and for regulating the inflation displacement of said inverted bag.

9. A flotation bag and a cylinder-piston transfer valve control mechanism in combination comprising an inflatable bag, a hollow cylinder having an inlet port, an outlet port in said cylinder communicating with said bag, a closure cap on the inlet end and a head having a hole therethrough on the outlet end of said cylinder, a piston head adapted to longitudinal movement within said cylinder, a piston rod attached at one end to said piston head and longitudinally guided through said hole in said head, a remote control manually operable cable attached to said rod, whereby when fluid pressure enters the inlet of said cylinder said pressure forces said piston head past said outlet port to inflate said bag and compresses said washer between said heads thereby sealing the cylinder chamber against leakage from said bag past said rod.

10. A cylinder-piston transfer valve mechanism comprising in combination a hollow cylinder having an inlet port and an outlet port longitudinally located through its wall, a closure cap on the inlet end and a head having a hole therethrough on the outlet end of said cylinder, a piston head adapted to longitudinal movement within said cylinder, a piston rod attached at one end to said piston head and longitudinally guided through said hole in said head, a remote control manually operable cable attached to said rod, resilient means associated with said cable and said rod to restrain said piston head to an intermediate position between said inlet and said outlet ports, whereby when fluid pressure enters the inlet of said cylinder said pressure forces said piston head past said outlet to thus transfer said pressure to said outlet of said cylinder and whereby upon substantial reduction of said pressure said cable returns said piston head to said intermediate position thereby isolating said ports from each other.

11. In an airplane flotation system, a flotation bag, a cylinder-piston transfer valve mechanism comprising in combination a hollow cylinder having an inlet port and an outlet port longitudinally located through its wall, said outlet port communicating with said bag, a closure cap on the inlet end and a head having a hole therethrough on the outlet end of said cylinder, a piston head adapted to longitudinal movement within said cylinder, a piston rod attached at one end to said piston head and longitudinally guided through said hole in said head, a packing washer mounted upon said piston rod within said cylinder between said piston head and said cylinder head, whereby when fluid pressure enters the inlet of said cylinder said pressure forces said piston head past said outlet port to inflate said bag and compresses said washer between said heads thereby sealing the cylinder chamber against leakage from said bag past said rod.

12. In an airplane emergency flotation system, a selective control valve mechanism associated therewith comprising a body member having a chamber; an inlet thru a wall of said chamber, a multiple number of outlets and a vent thru a second wall of said chamber; a check valve member adapted to close said inlet against reverse flow of fluid therethru; a rotatable disc valve member multiply slotted on one face and located within said chamber, one of said slots extending to the periphery of said disc, a rotatable shaft attached to said disc and extending through said second wall of said chamber, a handle attached to said shaft; a compression spring adapted to simultaneously restrain the slot-

ted face of said disc to intimate contact with said wall of said chamber and to seat said check valve member; said disc adapted by its relation to said outlets and by rotation of said shaft to selectively register either of said outlets with said slot leading to said chamber, or to close said outlets from each other and said chamber, or to register one of said slots with one of said outlets and said vent, and whereby depression of said disc by manual pressure on said handle releases said disc from the wall of said chamber to simultaneously vent said chamber and said outlets to atmosphere through said vent thereby controlling the flotation characteristics of said system.

13. In an airplane emergency flotation system, a selective control valve mechanism associated therewith comprising a body member having a chamber; an inlet thru a wall of said chamber, a multiple number of outlets and a vent thru a second wall of said chamber; a rotatable disc valve member multiply slotted on one face and located within said chamber, one of said slots extending to the periphery of said disc, a rotatable shaft attached to said disc and extending through said second wall of said chamber, a handle attached to said shaft; a compression spring adapted to restrain the slotted face of said disc to intimate contact with said wall of said chamber, said disc adapted by its relation to said outlets and by rotation of said shaft to selectively register either of said outlets with said slot leading to said chamber, or to close said outlets from each other and said chamber, or to register one of said slots with one of said outlets and said vent, and whereby depression of said disc by manual pressure on said handle releases said disc from the wall of said chamber to simultaneously vent said chamber and said outlets to atmosphere through said vent, thereby controlling the flotation characteristics of said system.

14. In an airplane emergency flotation system, means for inflating the flotation bodies of said system, means for supplementing the inflation of said bodies, a selective control valve mechanism associated with said supplemental means and said bodies comprising a member having a chamber; an inlet thru a wall of said chamber, a multiple number of outlets and a vent thru a second wall of said chamber; a rotatable disc valve member multiply slotted on one face and located within said chamber, one of said slots extending to the periphery of said disc, a rotatable shaft attached to said disc and extending through said second wall of said chamber, a handle attached to said shaft, a compression spring adapted to restrain the slotted face of said disc to intimate contact with said wall of said chamber, said disc adapted by its relation to said outlets and

by rotation of said shaft to selectively register either of said outlets with said slot leading to said chamber, or to close said outlets from each other and said chamber, or to register one of said slots with one of said outlets and said vent, and whereby depression of said disc by manual pressure on said handle releases said disc from the wall of said chamber to simultaneously vent said chamber and said outlets to atmosphere through said vent.

In testimony whereof, I hereunto affix my signature.

FRANK M. SALISBURY.
